UNITED STATES PATENT OFFICE.

ANDREW NELSEN, OF CHICAGO, ILLINOIS.

CAN-POLISHING MACHINE.

1,415,258.

Specification of Letters Patent. Patented May 9, 1922.

Application filed November 22, 1920. Serial No. 425,604.

To all whom it may concern:

Be it known that I, ANDREW NELSEN, a citizen of the United States, residing at Chicago, in the county of Cook and State of Illinois, have invented certain new and useful Improvements in Can-Polishing Machines, of which the following is a specification.

This invention relates to machines for buffing and polishing the exterior surfaces of metal cans, pails, and like articles, being adapted to handle the same either with or without the usual bails.

In an application filed by me on the second day of August, 1920, serial No. 400,686, I have disclosed and claimed a machine designed to polish the exterior cylindrical surfaces of pails and cans. My present invention is in the nature of an improvement upon the said machine, whereby it is adapted to polish not only the sides, but also the ends of such articles.

The principal object of the present invention is to provide a simple and efficient machine for the purpose stated, capable of buffing and polishing both the sides and one end of a can, pail or like article during a single passage of the latter through the machine, and wherein all the operations, except feeding the cans or pails to the machine, are automatic. Another object is to provide a machine of the character stated capable, with slight adjustment, of handling cans and pails of considerably varying sizes.

Still other objects and advantages of the invention will be apparent to those skilled in the art as the same becomes better understood by reference to the following description, taken in connection with the accompanying drawings, wherein I have illustrated one practical embodiment of the invention, and in which—

Fig. 1 is a side elevation of the complete machine;

Figs. 2 and 3 are vertical cross-sections taken on the lines 2—2 and 3—3, respectively, of Fig. 1;

Fig. 4 is an end elevation, viewed from the right of Fig. 1; and

Fig. 5 is a sectional detail taken on the line 5—5 of Fig. 4.

Referring to the drawings—

6 designates the side sills and 7 the end sills of a rectangular horizontal supporting

frame, itself supported on legs 8. Mounted on the horizontal frame are a pair of vertical rectangular frames, each comprising side uprights 9 and upper cross-bars 10. Between the uprights of the rear vertical frame is a lower cross-bar 11 (Fig. 3), and journaled in bearings 12 carried by the cross bar 11 and in bearings 13 mounted on the end frame member 7 are the spindles of a pair of horizontal rollers 14.

The inner edges of the frame uprights 9 are grooved, as shown at 15 in Fig. 5 to receive tongues 16 on the ends of a pair of cross-heads 17, beneath and between which are journaled a pair of parallel shafts 18 on which are keyed a pair of buffing or polishing rolls 19. The cross-heads 17 are centrally apertured in a vertical direction to receive adjusting bolts 20 swiveled therein, said bolts extending upwardly through similar apertures in the upper cross-bars 10 and provided on their upper threaded portions with adjusting nuts 21 connected to operate in unison by a sprocket-chain 21^a. On one of the nuts 21 is a hand wheel 21', by turning which in one direction or the other, the cross-heads 17 carrying the buffing and polishing rolls can be adjusted up and down in an obvious manner. The two rolls 19 are driven in opposite directions as indicated by the arrows in Fig. 3, for which purpose the roll shafts are equipped at one end with pulleys 22 driven at high speed from suitably applied belts (not shown) which permit a limited vertical adjustment of said pulleys.

Secured to one of the cross-heads 17 is an L-shaped bearing bracket 25, the vertical limb of which carries a bearing 26 for a horizontal stub shaft 27, on the inner end of which is a worm gear 28 driven by a worm 29 fast on the end of one of the buffing roll shafts 18. On the outer end of said shaft 27 is a miter-gear 30 that drives a mating miter-gear 31 journaled in a bearing 32 carried by the horizontal limb of the bracket 25. Extending through the miter-gear 31 and splined to the latter is a vertical shaft 33 journaled at its lower ends in a bearing 34 on the frame upright 9, and carrying at its lower end a miter-gear 35 in mesh with a mating miter-gear 36 fast on one end of a horizontal shaft 37. This

shaft 37 is journaled in bearings 38 and 38' on the lower cross-bar 11 and frame bar 6, and carries spiral gears 39 in mesh with spiral gears 40 keyed on the shafts of the 5 rollers 14, and driving the latter both in the same direction.

The cans to be polished on their sides are caused to travel endwise between and below the buffering rolls 19, for which purpose an endless conveyor chain is provided driven from the shaft 37. This chain, designated by 41, is trained over end sprockets 42 and 43, the sprocket 42 being journaled in bearings 44 (Fig. 4), and the sprocket 43 being keyed on the shaft 37. The chain 41 carries a series of flights 45 pivoted thereon at uniform intervals thereof, and each flight is provided with a tail-piece 45', carrying a pin 46 that engages with a guide groove or channel 47 that 20 extends parallel with and slightly below the upper lap of the conveyor chain 41.

The guide groove 47 extends around the axis of the conveyor sprocket 42 at the receiving end of the machine as shown in Fig. 25 1, and is formed with a flaring mouth 47' adapted to receive the pin 46 as the downwardly overhanging flight on the lower lap of the conveyor rounds the sprocket at the receiving end, and thereby guide the flight 30 into its working position to push the cans or pails past the buffering rolls 19.

The machine as thus far described is substantially identical with the machine disclosed and claimed in my former application, 35 herein above identified. To render the machine more perfect and complete as a can polishing machine, and to adapt it to the polishing of either or both ends, as well as the sides of the can, I have added to the apparatus thus far described a mechanism by which 40 the cans after they have passed the buffering rolls 19, are turned upright or on end and then advanced past a third buffering roll which polishes the upper end of the can. Describing 45 this latter feature, on the main horizontal frame is mounted a third upright rectangular frame consisting of side members 48, and an upper cross member 49. The side members 48 are vertically slotted, as shown at 51, 50 and through these slots extends a shaft 52, on which is keyed a third buffering roll 53 disposed with its axis crosswise of the machine and at right angles to the axes of the buffering rolls 19. The shaft 52 is journaled in the lower 55 ends of the arms of a yoke 54 that is slidable in the frame uprights 48 by a tongue and groove joint like that shown in Fig. 5, and this yoke is adjusted up and down by a rod 20' swiveled in the yoke and extending 60 through an aperture in the upper cross bar 49 and equipped with an adjusting nut and hand wheel 21^b this yoke adjusting means being identical with the cross-head adjusting means previously described.

65 The roll shaft 52 is conveniently driven

from one of the roll shafts 18 by the following mechanism.

Referring to Fig. 3, secured to the cross-head 17 is a bracket 55 carrying a horizontal bearing sleeve 56 in which is journaled a stub 70 shaft 57. On the inner end of this shaft is a miter-gear 58 driven by a miter-gear 59 on the adjacent end of the roll shaft 18. Keyed on the outer end of the stub shaft 57 is a miter-gear 60 that meshes with and drives a 75 miter-gear 61 splined on a shaft 62 extending lengthwise of the machine between the intermediate and rear roll supporting frames. This shaft 62 is journaled at one end in the arms of a U-shaped bearing-block 63 that is 80 swiveled on the stub shaft 57 behind the miter-gear 60. The other end of the shaft 62 is journaled in the arms of a U-shaped bearing-block 64 swiveled on the roll shaft 52, and said shaft 62 carries a miter-gear 65 drivingly engaged with a miter-gear 66 fast on the end of the roll shaft 52. Through the mechanism last described, a drive is transmitted to the rear buffering roll 53 from one of the buffering rolls 19, and this transmission is 90 of such a character as to permit the independent vertical adjustment of the buffering rolls 19 and 53 without any interference with the operation of the transmission mechanism.

It remains to describe the means for moving the cans from the side polishing mechanism to and past the end polishing roll 53, and for turning the can on end during such movement. Secured to and extending rearwardly from the intermediate frame uprights 9 are a pair of guide rails 67, which are additionally supported by strips 68 bent upwardly from horizontal strips 69 stepped on a pair of cross-beams 50 and 50'. From the uprights 9, the guide rails 67 converge 100 as shown in Fig. 3, for a limited distance, whence they extend parallel beneath the polishing roll 53. Also extending rearwardly from the forward ends of the rollers 14 are a pair of rails 70, which terminate in downwardly inclined portions 71 stepped upon the strips 69. These rails constitute a track for the cans, the latter being guided onto, and maintained on, said track by the guide rails 67.

Extending forwardly from the lower end of this track are a pair of endless conveyor chains 72 carried over sprockets 73 and 74 journaled on cross shafts 75 and 76 respectively. The chains 72 are equipped with 120 flights 77 which, as clearly shown in Fig. 1, engage with the rear sides of an upstanding can and push it past the polishing roll 53; said flights also serving to support the can against the backward push of the polishing roll and prevent its being overturned.

The conveyors 72 are driven from the shaft 37 by a sprocket chain 78 running over a sprocket 79 on one end of the shaft 37, and a sprocket 80 on one end of the shaft 75.

It is believed that the operation of the machine will be readily apparent from the foregoing description of its structure and organization. The attendant stands at the 5 rear or receiving end, which is the right end as shown in Fig. 1, and places the cans or pails, indicated at C successively on the long rollers 14. The can is at once rotated on its own axis by frictional contact with the rotating rollers 14, and as soon as the next 10 flight 45 engages with the rear end of the can it is pushed endwise, while still rotating, into and through the field of action of the buffering rolls 19 by which its exterior cylindrical surface is polished.

Since the buffering rolls turn in opposite directions, their rotating effects on the can are neutralized, and the can or pail continues to turn while passing through the field of 20 action of the rolls, so that it is polished throughout its entire circumference. After passing the buffering rolls 19, the can or pail is pushed off the delivery end of the conveyor into the track 70, being suitably 25 guided in a forward direction by the guide rails 67. As it slides down the inclined portion 71 of the track it is turned on end by the downward pitch of the track and the push of the flight 45, and immediately thereafter 30 it is engaged by a pair of the flights 77 and pushed forwardly past the buffering roll 53, by which latter its top surface or lid is thoroughly polished. Obviously, if it is desired to also polish the other end of the 35 can, the latter can simply be passed through the machine again with its other end foremost.

For polishing of larger or smaller size cans, the buffering rolls are adjusted upwardly 40 or downwardly by manipulation of the hand wheels 21' and 21^{1/2}. This capability of the machine, by a simple adjustment of the positions of the buffering rolls, to handle cans and pails of considerably varying sizes, constitutes one of the most important features of 45 the present invention, since it greatly enlarges its capacity and utility as compared with machines capable of handling but a single fixed size of cans or pails.

50 I claim:

1. In a can polishing machine, the combination with a pair of parallel horizontally journaled buffering rolls, and a horizontal conveyor for causing cans to travel endwise beneath and between said rolls, of a third horizontally journaled buffering roll beyond 55 and at right angles to said pair of buffering rolls, a conveyor for causing the cans to travel sidewise beneath said third roll, and means for guiding the cans and turning them on end between said rolls.

2. In a can polishing machine, the combination of a frame, a pair of parallel oppositely rotating buffering rolls horizontally

journaled therein, a conveyor for moving 65 cans endwise beneath and between said buffering rolls, including means for turning said cans on their axes while traveling past said buffering rolls, a third buffering roll horizontally journaled in said frame beyond and at right 70 angles to said pair of buffering rolls, a conveyor for moving the cans beneath said last named buffering roll, and means for guiding the cans to said last-named conveyor, including means for turning the cans on end 75 while passing onto said last named conveyor.

3. In a can polishing machine, the combination of a frame, a pair of parallel oppositely rotating buffering rolls journaled in and lengthwise of said frame, a conveyor for 80 moving cans endwise beneath and between said rolls, including means for turning said cans on their axes while traveling past said buffering rolls, a third buffering roll journaled in and transversely of said frame beyond 85 said pair of buffering rolls, a second conveyor beyond and in line with said first named conveyor for carrying the cans beneath said third buffering roll, and an inclined guide between said conveyors by which the cans 90 are delivered upright onto said second conveyor.

4. In a can polishing machine, the combination of a frame, a pair of oppositely rotating buffering rolls journaled therein, a conveyor for moving cans endwise past said buffering rolls, including means for turning said cans on their axes while traveling past said buffering rolls, a third buffering roll journaled in said frame beyond, and on an axis 100 at right angles to the axes of, said pair of buffering rolls, a conveyor for moving the cans past said last-named buffering roll, a downwardly inclined track for the cans by which they are turned on end between said pair 105 of buffering rolls and said third buffering roll, and means for guiding and supporting the cans laterally during their travel on said track and said last-named conveyor.

5. In a can polishing machine, the combination of a frame, a pair of parallel horizontal buffering rolls journaled in and lengthwise of said frame and serving to polish the sides of cans, means for simultaneously and 110 equally adjusting said rolls vertically in said frame, a third buffering roll in rear of said pair of rolls for polishing the ends of the cans, means for bodily adjusting said third roll vertically in said frame, transmission mechanism from one of said pair of rolls to 115 said third roll permitting independent adjustment of either of said rolls, and means for causing cans to travel past said rolls.

6. In a can polishing machine, the combination of a frame, a pair of parallel horizontal buffering rolls journaled in and lengthwise of said frame and serving to polish the sides of cans, means for simultaneously and 120

equally adjusting said rolls vertically in said frame, a third buffing roll for polishing the tops of the cans disposed in rear of said pair of rolls on an axis at right angles to the axes of the latter, means for bodily adjusting said third roll vertically in said frame, transmission mechanism from one of

said pair of rolls to said third roll permitting independent adjustment of either of said rolls, means for causing cans to travel 10 past said rolls, and means for turning the cans from horizontal to upright position during said travel.

ANDREW NELSEN.
